[57] ABSTRACT

A clear, homogeneous, aqueous fabric softening composition contains a solubilized tetraalkyl quaternary ammonium salt having two short-chain alkyl groups and two long-chain alkyl groups, about 5 percent to about 25 percent of the latter having methyl and ethyl branching on the 2-carbon; the solubilizers comprising aryl sulfonates, diols, ethers, low molecular weight quaternaries, sulfobetaines, alkyl taurines, amine-, phosphine-, and sulfoxides, and nonionic surfactants, some of the foregoing having utility only as auxiliary solubilizers.

6 Claims, No Drawings

CLEAR FABRIC-SOFTENING COMPOSITION

BACKGROUND OF THE INVENTION

1. Field of the Invention

Traditionally, fabric softening compositions have been marketed in the form of opaque, liquid suspensions and have been prone to cause turbid, agglomerated, non-dispersed clumps of active softener components upon addition to rinse water in an automatic washing machine. Furthermore, if sufficient amounts of anionic detergent are carried over into the rinse water, an undesirable co-precipitate of detergent-softener active may be deposited on the treated fabrics. The fabric-softening compositions of the present invention are in solution, or at least in visually clear colloidal dispersion, and in concentrated form and do not cause turbidity in diluted concentrations in the rinse water even with anionic or other detergent active present. Further, when traditional fabric softener compositions which are based on dimethyl di(hardened tallow) ammonium halide or 2-heptadecyl-1-methyl-1-(stearoyl amido ethyl) imidazoline methosulfate are exposed to the atmosphere in an uncapped bottle or in an open vessel such as a washing machine automatic open cup dispenser, a rubbery skin forms over the surface which is not readily dispersible in the rinse water. These skins also have a tendency to adhere to and build up on the walls of cup dispensers. In contrast, the products of the instant invention drain substantially completely from automatic dispensing assemblies, leaving at most only a slight film, forming minimal objectionable insoluble matter.

Heretofore, the quaternary ammonium halide employed in household fabric-softening compositions has been dimethyl di(hardened tallow)quaternary ammonium chloride, or a closely homologous substance, the term "hardened tallow" in this instance denoting alkyl groups, principally palmityl and stearyl, derived from hydrogenated tallow. This quaternary is not readily amenable to solubilization, and the desire to formulate a clear fabric softening composition necessitated a substantially complete reformulation of traditional fabric-softening compositions.

2. The Prior Art

U.S. Pat. No. 3,033,704

Discloses the use of dimethyl di(hydrogenated tallow) alkyl quaternary ammonium chloride in conjunction with an organomericurial germicide for the treatment of fabrics.

U.S. Pat. No. 3,122,502

Discloses a fluid colloidal aqueous preparation comprising at least one cationic fabric softener and at least one organomericurial germicide. The germicide may be slurried with hexylene glycol in the manufacture of the product. The hexylene glycol remains in the product in small amounts but has no disclosed solubilizing action.

U.S. Pat. No. 3,154,489

Discloses that quaternary ammonium salts and anionic detergents are compatible in the presence of a polyoxyethylenefatty amine condensation product.

U.S. Pat. No. 3,216,944

Discloses that aqueous suspensions of dimethyl di(hardened tallow) alkyl quaternary ammonium salt is stabilized against phase separation by the presence of 3,4,4'-trichlorocarbanilide.

U.S. Pat. No. 3,296,145

Discloses that amine oxides are compatible with germicidal water-soluble quaternary ammonium salts having one long alkyl chain. Mixtures of at least one compound of each of these classes can be prepared in aqueous liquid form as surgical scrub.

U.S. Pat. No. 3,325,404

Teaches that anionic surfactants precipitate di-(long-chain)alkyl-dimethyl ammonium chloride and like quaternaries when mixed therewith in an aqueous medium, and that the precipitation is inhibited by the presence of a mono(long-chain)-tri(short-chain)alkyl or alkylaryl quaternary ammonium compounds.

U.S. Pat. No. 3,360,470

Discloses that sodium carboxymethylcellulose inhibits its yellowing of textile materials by quaternary ammonium fabric softeners when used in water containing colored colloidal particles.

U.S. Pat. No. 3,364,142

Discloses that quaternary ammonium fabric softeners in aqueous suspension are rendered freeze-thaw stable by the addition of a condensate of a fatty alcohol and ethylene oxide.

U.S. Pat. No. 3,395,100

Discloses that a di(isostearyl)dimethyl quaternary ammonium chloride can be prepared as a highly concentrated, e.g., 75 percent, fluid product in a water-miscible solvent such as hexylene glycol, Butyl Cello-solve, or an isopropanol-water mixture. The quaternary is readily dissolved in small amounts of solvent. The precise structure of the isostearyl radical is not accurately known.

U.S. Pat. No. 3,454,494

Discloses that a condensation product of a fatty acid derivative and a polyfunctional amine (e.g., diethanol-amine) has fabric-softening properties and that in admixture with a nonionic surfactant (e.g. an alcohol-ethylene oxide condensate) is compatible with anionic detergents in the wash cycle.

U.S. Pat. No. 3,501,335

Discloses that N,N-dimethyl-N-2-hydroxystearyl amine oxide, and related compounds have fabric-softening properties.

SUMMARY OF THE INVENTION

45 It has now been discovered that a visually clear aqueous fabric-softening composition can be prepared containing about 2 to about 20 percent of a dimethyl-di(long chain) quaternary ammonium chloride having a long-chain mixture of particular molecular configurations, and one or more solubilizers.

50 It is therefore an object of the present invention to prepare a visually clear aqueous fabric-softening composition.

55 It is another object of the invention to prepare a physically stable aqueous fabric-softening composition.

It is a further object of the invention to prepare a clear, aqueous fabric-softening composition which forms a clear dispersion when diluted to use concentration.

60 In one embodiment of the invention there is produced a visually clear aqueous fabric-softening composition which remains clear after having been subjected to temperatures ranging from about 0°F to about 125°F, and restored at room temperature.

65 The term "fabric softening composition" as used herein denotes a composition containing one or more components which bring about a desirable change in

sensory and/or physical characteristics of cloth when the cloth is subjected to treatment by the compositions in an aqueous medium, and dried. It is an object of the fabric-softening treatment to impart a soft and pleasing feel to fabrics which would otherwise tend to be harsh and stiff.

Of particular utility are the solubilizers which do not produce foam. Accordingly in a preferred embodiment of the invention there is provided a non-foaming, clear liquid fabric softening composition.

It has been found that, unlike the di-(hardened tal-low) quaternary customarily used, a quaternary of related structure but having from about 5 to about 25 percent 2-(short chain)alkyl branching on the long-chain alkyl groups, and having a specified chain length distribution, can be solubilized to produce a clear aqueous fabric-softening composition.

As set forth in Example 14, a use concentration (equivalent to about 2 fluid ounces of whose composition in 17 gallons of water) of quaternary A without a solubilizer is turbid, but a use concentration of a product of the invention is visually clear. Use concentrations will vary with the user, but in general will range from about 1 to about 4 fluid ounces of the whole composition per 17 gallons of water. The product of the present invention has excellent fabric-softening characteristics, in opposition to the teachings of U.S. Pat. No. 3,501,335 wherein it is disclosed that fabric-softening agents must be only marginally soluble, that is, the solute is in colloidal dispersion, rather than being in true solution (column 2, lines 40-53).

The quaternary ammonium fabric softener referred to is a mixture having two long alkyl chains and two short alkyl chains, the long alkyl chains being a mixture of straight and branched configurations. It is described in and claimed in combination with certain amine oxides in U.S. application Ser. No. 788,918, now issued as U.S. Pat. No. 3,660,286, which is hereby incorporated by reference.

The aforementioned quaternary ammonium mixture has the following formula

wherein R_1 and R_2 are independently selected from the group consisting of

and

Radical II: $CH_3(CH_2)_4$ —and mixtures thereof, wherein

$m = 8$ through 14 inclusive,

$y = 11$ through 17 inclusive, and

Radical I comprises between about 5 and about 25 percent by weight of the total of R_1 and R_2 , and Radical

II comprises between about 40 and about 60 percent by weight of carbon chains where y is 11 through 14 inclusive, with the remainder being carbon chains where y is 15 through 17 inclusive,

5 R_3 and R_4 are independently selected from the group consisting of methyl, ethyl, propyl, and isopropyl radicals,

R_5 is methyl or ethyl, and

10 X is an anion selected from the group consisting of chloride, bromide, iodide, methosulfate, and ethosulfate, which imparts water dispersibility to the quaternary.

The specific quaternary mixture employed in the examples set forth hereinafter has the following analysis:

Chain Lengths Of Long Chain Alkyls	% By Weight, Based on Total Long-Chain Alkyl
C_{12}	11.5
C_{13}	17.0
C_{14}	17.0
C_{15}	11.0
C_{16}	28.0
C_{17}	15.0
C_{18}	0.5
C_{20}	
	100.0

About 12.5 percent of the long-chain alkyl groups bear a methyl or ethyl group on the 2-carbon, and these are confined to the C_{12} - C_{15} alkyl groups, as described above. The remainder of the long-chain alkyl groups, about 87.5 percent, are straight chain and comprise about 40-60 percent C_{12} - C_{15} chain lengths and about 60-40 percent C_{16} - C_{18} chain lengths, these two last-named ranges being based on the total of the long-chain alkyl groups having a straight-chain configuration.

Substances which serve to solubilize the quaternary used in the aqueous compositions of the invention fall within the classes of lower molecular weight alcohols, 40 aryl sulfonates, C_2 - C_6 diols, water-soluble low molecular weight ethers, water-soluble quaternaries, sulfobetaines, alkyl taurines, amine oxides, phosphine oxides, sulfoxides, and nonionic surfactants. Mixtures of 45 two or more of the aforementioned substances have been found to be advantageous.

The non-foaming solubilizers comprise, for example the arylsulfonates, alkanediols, alkylene glycols having 2-6 carbon atoms, the methyl, ethyl, or butyl monoethers of diethylene glycol, and 2-methoxy, 2-ethoxy, or 2-butoxy ethanol.

50 More specifically among the species effective as solubilizers in the presence of water within the above-listed classes there may be mentioned the following:

55 LOW MOLECULAR WEIGHT ALCOHOLS

methanol, ethanol, 1-propanol, isopropanol, and tert-butanol

DIOLS

60 ethylene glycol, 1,3-propanediol, 1,4-butanediol, 1,5-heptanediol, and 1,6-hexanediol

WATER-SOLUBLE LOW-MOLECULAR WEIGHT ETHERS

65 the monomethyl, monoethyl, and monobutyl ethers of diethylene glycol, and the methyl, ethyl, and butyl monoethers of ethanol

WATER-SOLUBLE QUATERNARY AMMONIUM COMPOUNDS

dodecyl-dimethyl-benzyl ammonium chloride, dodecyl-dimethyl-ethylbenzyl ammonium chloride, myristyl-dimethylbenzyl ammonium chloride, myristyl-dimethyl-ethylbenzyl ammonium chloride, dioctyl-dimethyl ammonium chloride, and didecyl-dimethyl ammonium chloride, and mixtures thereof

SULFOBETAINES

N-decyl sulfobetaine, N-dodecyl sulfobetaine, N-coco sulfobetaine wherein "coco" designates mixed alkyl groups having the molecular weight distribution of coconut oil fatty acids, and mixtures thereof

N-(2-hydroxyalkyl)methyl taurines

N-(2-hydroxyoctyl)methyl taurine, and N-(2-hydroxy-decyl) methyl taurine, and mixtures thereof

AMINE OXIDES

N,N-dimethyl-N-octyl amine oxide, N,N-dimethyl-N-decyl amine oxide, N,N-dimethyl-N-dodecyl amine oxide, N,N-dimethyl-N-tetradecyl amine oxide, N,N-dimethyl-N-hexadecyl amine oxide, N,N-bis(2-hydroxyethyl)-N-dodecyl amine oxide, N,N-bis(2-hydroxyethyl)-N-tetradecyl amine oxide, and mixtures thereof

PHOSPHINE OXIDES

Dimethyl decyl phosphine oxide, dimethyl dodecyl phosphine oxide, dimethyl tetradecyl phosphine oxide, dimethyl hexadecyl phosphine oxide, and mixtures thereof. These phosphine oxides have no solubilizing action alone, but their inclusion in the composition lessens the amount of other solubilizers, particularly isopropanol, that may be required to form a clear aqueous product.

SULFOXIDES

Methyl hexyl sulfoxide, methyl heptyl sulfoxide, methyl octyl sulfoxide, methyl nonyl sulfoxide, methyl decyl sulfoxide, dodecyl-2-hydroxyethyl sulfoxide, and mixtures thereof.

ARYLSULFONATES

Sodium benzenesulfonate, sodium xylenesulfonate, sodium tolenesulfonate, sodium cumenesulfonate, and the corresponding potassium, ammonium, and substituted ammonium salts, and mixtures thereof. These compounds are not effective as sole solubilizers, but may be used to advantage to lower the amount of other solubilizers.

NONIONIC SURFACTANTS

Among the nonionic materials that can be employed in the fabric softening compositions of the invention are the Pluronics (trademark of the Wyandotte Chemicals Corp.), formed by condensing propylene oxide with propylene glycol to a molecular weight of about 600-2500 to form a base followed by condensing ethylene oxide to this base to the extent of about 30 to about 90 percent by weight, total molecule basis. U.S. Pat. Nos. 2,674,619 and 2,677,700 describe operable nonionic compounds; compounds formed by the simultaneous polymerization of propylene oxide and ethylene oxide, and containing randomly positioned oxypropyl-

ene and oxyethylene groups, and having over 30 percent ethylene oxide by weight. These and related compounds are described in U.S. Pat. Nos. 2,979,528; 3,036,118; 3,022,335; 3,036,130, and 3,048,548, alkyl phenols having 6-12 carbon atoms in the alkyl portion, (straight or branched) ethoxylated with 6-25 molar proportions of ethylene oxide, ethoxylates of fatty alcohols having 8-18 carbon atoms per mole and 5 to 30 molar proportions of oxyethylene groups.

- 5 10 Examples of specific nonionic compounds branched-chain branched nonyl phenol condensed with 8-14 molar proportions of ethylene oxide, a mixed C₁₁-C₁₅ secondary alcohol (Tergitol 15-S) condensed with 9-14 molar proportions of ethylene oxide, a mixed C₁₄-C₁₅ alcohol made by the Oxo process (Neodol 45) condensed with 9-12 moles ethylene oxide, or a mixture of 65 percent C₁₄ and 35 percent C₁₅ synthetic straight chain primary alcohols condensed with 9-15 molar proportions of ethylene oxide.
- 15 20 In accordance with the invention, it is contemplated that the solubilizers will be used in the following proportions by weight of the whole composition:
  1. Arylsulfonates having the formula A-Bz-SO₃M wherein A is H, methyl, dimethyl, or isopropyl, Bz is a benzene nucleus, and M is Na, K, NH₄, or substituted ammonium, such as mono-, di-, or triethanolammonium, tetraethyl ammonium, morpholinium, etc., 0 to about 40 percent;
  2. Amine oxides having the formula R¹R²R³N → 0 wherein R¹ and R² are selected from the group consisting of methyl, ethyl, propyl, isopropyl and 2-hydroxyethyl, and R³ is selected from the group consisting of alkyl and 2-hydroxyalkyl having about 8 to about 14 carbon atoms, 0 to about 37 percent;
  3. Alkanediols having 2-6 carbon atoms, 0 to about 40 percent;
  4. Alkylene glycols and polyoxy alpha-omega diol having 2-6 carbon atoms, 0 to about 40 percent;
  5. Low molecular weight, i.e., the 2-methoxy, 2-ethoxy, and 2-butoxy monoethers of ethanol, and the methyl, ethyl, and butyl monoethers of diethyleneglycol;
  6. Water-soluble quaternary ammonium compounds having the formula R¹R²R³R⁴NCI wherein R¹ is an alkyl group having about 8 to about 14 carbon atoms, R² and R³ are methyl, and R⁴ is benzyl or ethylbenzyl, 0 to about 30 percent;
  7. N-alkyl sulfobetaines having the formula

wherein R is an alkyl group having 10-14 carbon atoms, 0 to about 20 percent;

- 50 60 8. N-2-hydroxymethyl taurines, wherein the alkyl group has 8 to 10 carbon atoms, 0 to about 30 percent;
9. Phosphine oxides having the formula R¹,R²,R³P → 0 wherein R¹ and R² are methyl, and R³ is an alkyl radical having from about 10 to about 16 carbon atoms, 0 to about 20 percent;
10. Sulfoxides having the formula R¹R²S = 0 wherein R¹ is a methyl, ethyl, or a 2-hydroxyethyl radical,

and R² is an alkyl radical having about 6 to about 10 carbon atoms, 0 to about 20 percent;

11. Nonionic surfactants selected from the group consisting of (a) ethylene oxide condensates of aliphatic alcohols having about 8 to about 18 carbon atoms, and (b) of alkylphenols having straight or branched chain alkyl groups with about 6 to about 12 carbon atoms, the ethylene oxide forming oxyethylene groups to the extent of 5 to 30 molar proportions per mole of condensate, and (c) ethylene oxide condensates with polyoxypropylene, having 30 to 90 percent ethylene oxide by weight per molecule, 0 to about 20 percent.

Mixtures of these solubilizers may be used. By the term "substituted ammonium" is meant N-alkyl substituted ammonium wherein said alkyl has 1-3 carbon atoms, N-alkanol, N,N-dialkanol, N,N,N-trialkanol substituted ammonium wherein said alkanol has 2-3 carbon atoms, morpholinium, and mixtures thereof.

Not every one of the useful solubilizers is effective when used alone. For example at a level of 6 percent quaternary fabric softening agent, clarity is not attained with up to 40 percent of a mixture of xylene- and toluenesulfonates as the sole solubilizer. Xylene- and toluenesulfonates however have utility in combination with other solubilizers. Also the phosphine oxides and non-ionic surfactants cannot be used alone. The remaining solubilizers disclosed as useful in accordance with the instant invention may be used alone or in admixture, and as shown below the minimum requirements vary. Consequently the useful solubilizers will be so selected as to species and proportions to provide a visually clear liquid medium containing about 2 to about 20 percent of the quaternary ammonium fabric softener of the type described herein. Preferred proportions of softener are from about 4 to about 12 percent. A particularly useful level is about 6 percent.

The solubilizer will be present in proportions ranging from about 4 to about 43 percent, preferably about 7 to about 24 percent, whole composition basis, the balance being essentially water, which, along with small quantities of optional components described elsewhere herein, comprise a solvent system which is present to the extent of about 98 to about 80 percent of the whole composition.

The expression "the balance essentially water" as used herein allows for the inclusion of unspecified optional ingredients that do not materially alter the basic and novel characteristics of the composition. For example, germicides, optical brighteners, bluing, colorants, etc. may advantageously be incorporated into the product.

Suitable optional germicides are alkyl dimethyl ethylbenzyl ammonium chloride (BTC 471); 4,2',4'-trichloro-2-hydroxy diphenyl ether (Irgasan CH 3565); 4',5-dibromosalicylanilide; 3,4',5-tribromosalicylanilide; and 2,2'-methylenebis (3,4,6-trichlorophenol) (Hexachlorophene).

It is often desirable to impart a whitening and brightening effect to cloths during the softening step. For this purpose the clear products of the invention may contain fluorescent optical brighteners and colorants. For example the sodium salt of 2-(stilbyl-4'')-(naphtho-1',2':4,5)-1,2,3-triazole-2''-sulfonic acid, a compound disclosed in U.S. Pat. No. 2,784,183, and a disulfonate corresponding in molecular structure to the foregoing, also disclosed in U.S. Pat. No. 2,784,183, may be incor-

porated in proportions of about 0.02 to about 0.2 percent to impart optical brightening to fabrics treated with the softener.

Other suitable optical brighteners that may optionally be used are sodium 4,4'-bis(2-phenyl-amino-4-morpholino-1,3,5-triazyl (6) diaminostilbene-2,2'-disulfonate; sodium 4,4'-bis (2,4-diphenylamino-1,3,5-triazyl (6) diaminostilbene-2,2'-disulfonate; sodium 4,4'-bis(2-phenylamino-4-diethanolamino-1,3,5-triazyl (6) diaminostilbene-2,2'-disulfonate (Calcofluor M2R); and sodium 4,4'-bis(2-phenylamino-4-morpholino-1,3,5-triazyl (6) diaminostilbene-2,2'-disulfonate (Calcofluor White RC Conc.).

Suitable optional colorants are 1,4-bis(2-ethylhexylamino)anthraquinone (Aviation Oil Blue); Acid Blue 80; C.I. 61585 (Polar Brilliant Blue RAW); Basic Violet 10, C.I. No. 45170 (D&C Red No. 19 - Rhodamine B); and C.I. Pigment Green 74260, a chlorinated copper phthalocyanine (Heliogen Green W Powder).

The colorants, when used, are desirably present at levels between about 0.003 and 0.2 percent, depending upon the depth of tinting desired. For example, Polar Brilliant Blue RAW may be used in amounts from about 0.003 to about 0.02 percent, and generally at a level of about 0.006 percent. Hastings Sky Blue OB may be present between about 0.05 and 0.01 percent, usually about 0.1 percent.

Viscosity is considered by many to play an important role in ease of measuring a prescribed volume of a liquid to be poured into a washing machine. A viscosity of about 200 to about 500 centipoises is satisfactory for minimizing over-dosing when pouring, particularly when, as currently practices, the cap of the container serves as a measuring cup. The broad range of useful viscosities is 1 to about 1000 centipoises. A preferred range is about 100 to about 500 centipoises. In a composition containing 6 percent quaternary fabric softener solubilized with dimethyl coco amine oxide and isopropanol, a desirable viscosity of 200 centipoises can be obtained by including in the composition 0.25 percent of hydroxyethylcellulose (Cellosize QP 52000-high) at an amine oxide level and an isopropanol level of about 7 percent each. The product may gel if higher proportions of hydroxyethylcellulose, or higher molecular weight amine oxides are used. Viscosity data at various levels of amine oxide and isopropanol in an aqueous composition containing 6 percent quaternary and 0.25 percent Cellosize are given below. "Cellosize" is a trademark of Union Carbide Co. "Coco" as used herein refers to the long-chain alkyl groups having the mixed molecular distribution in coconut oil, i.e., about 8 percent caprylic (C₈), 7 percent capric (C₁₀), 48 percent lauric (C₁₂), 17 percent myristic (C₁₄), 9 percent palmitic (C₁₆), 2 percent stearic (C₁₈), 6 percent oleic (C₁₈₋₂), and 3 percent linoleic (C₁₈₋₄).

15 ^(a)Clarity obtained at any proportion of these alcohols with water.

The following Examples will lead to a more complete understanding of the present invention. These Examples are for illustrative purposes only, and are not intended to be construed as defining the limits of the scope of the invention.

EXAMPLE 1

Low and intermediate molecular weight aliphatic alcohols solubilize the quaternary in the absence of water. Commercial preparations however will contain the maximum proportion of water permissible, consistent with clarity. In such compositions wherein the quaternary is present at a 6 percent level, the presence of a low-molecular weight alcohol clarifies an aqueous dispersion of the quaternary, provided the low-molecular weight alcohol is present in at least the following proportions, whole composition basis. 1-butanol and higher alcohols do not aid in the clarification in aqueous systems.

TABLE I

Alcohol	Minimum %
Methanol	39
Ethanol	25
Propanol	13.5
Isopropanol	16
Tert-butanol	15

An excellent clarifying mixture is composed of an aliphatic alcohol having 1-4 carbon atoms and dimethyl "coco" amine oxide wherein the long-chain alkyl group is a mixture having substantially the chain-length distribution of coconut oil fatty acids. In the case of alcohols having complete miscibility with water, i.e., the first five alcohols listed hereinbelow in Table II, there is a minimum critical proportion of the alcohol required to clarify an aqueous dispersion of the quaternary. Higher proportions of the alcohols may be used, up to the point at which the alcohol constitutes the entire solvent. In the case of 1-butanol and higher molecular weight alcohols having limited solubility in water, i.e., about 0.5 to 15 grams per 100 ml, clarity is achieved only within a narrow percentage range of alcohol in the presence of the aforementioned amine oxide. Examples of the aforementioned alcohol requirements for the clarification of 6 percent quaternary in the presence of 4 percent dimethyl "coco" amine oxide, the balance of the composition being water, are shown below.

10

TABLE II

	Alcohol	Percent by Weight
25	Quaternary ^(a)	6.0
	Isopropanol	20.0
	Water	74.0

15 ^(a)wherein 12.5% of the long-chain alkyl groups have branching on the 2-carbon as hereinbefore described (Formula A).

30 The above composition has the following characteristics:

pH	5.5
Viscosity	10 cps
Sp. Gr.	0.965
Cloud Point	50°F
Flash Point	
Closed Cup	about 80°F
Open Cup	about 100°F

40 Two ounces of the foregoing composition, as well as two ounces of similar compositions containing 30 and 40 percent isopropanol, in the rinse cycle of an automatic top-loading washer provide a softening effect on cotton equal to that of a product containing 6 percent dimethyl-di(hardened tallow) ammonium chloride in an aqueous medium without an alcohol.

EXAMPLE 3

50 The flash point of the compositions of Example 2 above can be lowered by substituting an amine oxide for a portion of the isopropanol. The amount of amine oxide required is less than the amount of isopropanol replaced. The relative proportions of isopropanol and dimethyl "coco" amine oxide required to solubilize 6 percent of the quaternary described in Example 1 are set forth below:

	Isopropanol	Amine Oxide
60	20.0	
	17.5	1.0
	15.0	2.0
	12.5	3.0
	10.0	4.0
	5.0	6.0
	2.0	7.2
65	0	8.0

EXAMPLE 4

Levels of about 1 to about 14 percent of the quaternary (A) can be solubilized in the aqueous medium by about 3 to about 20 percent of dimethyl coco amine oxide. In the compositions set forth below there is present from about 0.2 to about 2.8 percent isopropanol added as a part of the liquid vehicle associated with the quaternary as supplied by the manufacturer.

% Quaternary (A)	% Amine Oxide	% Isopropanol
1.0	3.0 ^(a)	0.2
3.0	4.0 ^(a)	0.6
5.0	20.0	1.0
6.0	7.0 ^(a)	1.2

14.0	20.0 ^(a)	2.8

^(a)turbid^(a)minimum proportions for clarity.

EXAMPLE 5

Lower molecular weight homologues of the quaternary fabric softeners of this invention, i.e., the dimethyl-dioctyl-, and the dimethyl-didecyl homologues, are effective solubilizers, as seen from the data below. In all cases the quaternary fabric softener is present at 6 percent in an aqueous medium. All percentage figures given are on the whole composition basis.

Alkyl groups	Minimum % for Clarity
dibutyl	phase separation
dihexyl	phase separation
dioctyl	5.2%
octyl decyl	4.8%
didecyl	14.0%
di coco	10%
di tallow	opaque emulsion
3.5 parts di C ₈ and 0.5 part di C ₁₀	4.0%
3.2 parts di C ₈ and 0.5 part C ₈ C ₁₀	3.7%

EXAMPLE 6

(Long-chain alkyl)dimethyl benzyl- and ethylbenzyl ammonium chlorides, wherein the long-chain alkyl group has 5-68 percent C₁₂, 30-60 percent C₁₄, and 0-30 percent C₁₆ chain lengths, are effective solubilizers for the fabric-softening quaternary of the present invention in 6 percent aqueous dispersion. Representative solubilizers are listed below, with the minimum percentage, whole composition basis, of each required to clarify.

TABLE III

MINIMUM % QUATERNARY REQUIRED TO CLARIFY 6% ADOGEN 432		Percent
alkyl ^(a) dimethyl benzyl ammonium chloride		8.0
alkyl ^(a) dimethyl ethyl benzyl ammonium chloride		8.0
alkyl ^(a) dimethyl benzyl/alkyl ^(a) dimethyl ethyl		8.0
benzyl ammonium chloride, 1:1 ratio		8.0
alkyl ^(a) dimethyl benzyl/alkyl ^(a) dimethyl ethyl		8.0
benzyl ammonium chloride, 1:1 ratio		8.0

^(a)50% C₁₂, 30% C₁₄, 17% C₁₆, 3% C₁₈^(b)50% C₁₂, 60% C₁₄, 30% C₁₆, 5% C₁₈^(c)68% C₁₂, 32% C₁₄

The above data show slight alkyl distribution variation does not affect the level of quaternary necessary for clarity with 6.0 percent Adogen 432 as is found with the dialkyl dimethyl quaternary compounds. Similarly, no difference is noted between the benzyl and ethyl benzyl form.

EXAMPLE 7

- 10 This example shows the effectiveness of certain long-chain alkyl-dimethyl sulfobetaines in clarifying an aqueous medium containing 6 percent quaternary.

Long-chain alkyl	Percent	Observation
stripped coco	7	clear
lauryl	7	turbid
lauryl	8	clear
coco	7	turbid
coco	8	clear
myristyl (C ₁₄)	12	very turbid
stearyl (C ₁₈)	12	phase separation

EXAMPLE 8

25 Mixtures of dimethyl coco amine oxide and medium chain length alkyl sulfobetaines are effective to clarify quaternary (A) in an aqueous medium, as exemplified below.

Quaternary	Amine Oxide	Sulfobetaine		
		Stripped Coco	dodecyl	coco
35	3	1	3	
	3	3	1	
	6	4	4	
	6	4		4
	6	4		

EXAMPLE 9

45 The following example shows the criticality of chain-length of 2-hydroxyalkylmethyltaurines for effective solubilization of a 6 percent aqueous dispersion of the fabric-softening quaternary. The chain length of the 2-hydroxyalkyl portion must be below C₁₂ for effective solubilization.

Methyl Taurine	Percent By Weight of Total Composition	Observations
2-Hydroxy-octyl-	7.0	slightly hazy
2-Hydroxy-octyl-	12.8	clear
2-Hydroxy-dodecyl-	27.0	hazy
Hydroxy-C ₁₅ -C ₁₆ -	24.0	hazy
Hydroxy-hexadecyl-		
(N-oxide)	15.0	opaque
Alkoxy(C ₁₂ -C ₁₃)hydroxy-		
propyl-	22.0	translucent gel

EXAMPLE 10

65 The N,N-dimethyl-N-alkylamine oxides are more effective in clarifying the quaternary ammonium compound of the instant invention (structure A), as the alkyl group is made shorter, as shown in the following

tabulation. The amine oxides employed are commercial products containing a minimum proportion of the stated chain length of the long-chain alkyl group as shown.

Chain length	Min. % to clarify 6% quaternary
95% C ₈	4.7
95% C ₁₀	4.6
95% C ₁₂	5.4
95% C ₁₄	8.4
95% C ₁₆	8.5
94% C ₁₂	6.3
90% C ₁₄	8.5
90% C ₁₆	13.5
90% C ₁₈	not clear at 20%

Proportions of dimethyl-C₁₂-amine oxide in the region of the minimum clarifying percentages cannot tolerate significant percentages of the C₁₈ homologue, as seen in the following table:

% Amine Oxide Whole Composition Basis	Observation After 1 Day
C ₁₂	C ₁₈
7	none
6	1
5	2
5	3
4.5	3

Other amine oxides are effective as clarifying agents for an aqueous 6 percent solution of the quaternary fabric softener, as shown below.

Amine Oxide	Minimum Percentage to Clarify - Whole Composition Basis
N,N-bis(2-hydroxyethyl) decyl-	8
N,N-bis(2-hydroxyethyl) coco-	8
N-methyl, N-(2-hydroxyethyl)-	
2-hydroxy(C ₁₅ -C ₂₀) amine oxide	8 (gel)
N-methyl-N-(2-hydroxyethyl)-	
2-hydroxy-octadecyl	8 (gel)

EXAMPLE 11

The data below show the action of dialkyl sulfoxides in the production of a clear quaternary aqueous fabric softening composition. The percentage figures shown are based on the whole composition.

% Qua- ternary	Sulfoxide	% Sulfoxide	Observation
6	dimethyl	50.0	hazy liquid
6	heptyl methyl	5.1	clear liquid
2	dodecyl methyl	2.0	opaque liquid
2	tetradecyl methyl	2.0	opaque liquid
3	hexadecyl methyl	3.0	opaque liquid
3	dodecyl methyl	3.0	clear aerated gel
3	dodecyl methyl	6.0	clear aerated gel
6	dodecyl methyl	5.0	clear semi- liquid gel

EXAMPLE 12

The following data illustrate the effect of a nonionic surfactant in combination with dimethyl coco amine oxide on an aqueous product containing 6% of quaternary (A). The nonionic surfactant employed is an alkoxyethoxyethylene ethanol wherein the alkoxy portion is composed of a mixture of chain lengths about 67 percent of which have 12 carbon atoms and about 33 percent of which 18 carbon atoms, and the oxyethylene groups are present to the extent of about 60 percent by weight of the molecule.

% Nonionic	Viscosity (cps)	Cloud Point	Initial	Stability 9 Months (R.T.)
—	30	44°F	clear	trace sediment
0.25	30	47°F	clear	trace sediment
0.50	30	47°F	clear	trace sediment
2.00	40	49°F	clear	trace sediment
5.00	40	41°F	clear	clear
10.00	70	56°F	clear	clear
20.00	140	61°F	clear	clear

Addition of less than 5 percent nonionic has little effect on viscosity. While the addition of 5-20 percent nonionic increases viscosity and improves room temperature stability, the increasing amounts of nonionic also increase the cloud point and result in decreased low temperature stability.

EXAMPLE 13

A typical clear fabric-softening composition has the following formula:

	Percent
Quaternary (A)	5-7
Dimethyl coco amine oxide	4-9
Isopropanol	3-15
Colorant (Polar Brilliant Blue)	0.005-0.015
Perfume	0.1-0.2
Water	balance
	100.00

The proportions of amine oxide and isopropanol will be selected with respect to the proportion of quaternary to provide a visually clear solution.

EXAMPLE 14

A clear homogeneous liquid fabric softening composition is prepared having the following formula.

	Percent By Weight
Quaternary (A)	6.0
Dimethyl coco amine oxide	7.0
(a)Isopropanol	3.0
Colorant (Polar Brilliant Blue)	0.01
Perfume	0.15
Water	Balance
	100.00

(a)added as a component associated with the quaternary and the amine oxide, which are commercial products containing respectively 15% and 30% isopropanol.

Two ml of the above-described composition are added to 2 liters of tap water (approximating use concentration) at about 110 ppm hardness as CaCO₃, at a

temperature of 120°F. The composition completely dissolves, whereas a similar composition without the amine oxide when tested in the same manner produces a turbidity.

EXAMPLE 15.

5

Desirable fabric softener compositions which are visually clear liquids are prepared having the following components in the indicated proportions:

- i. about 3 to about 7 percent of quaternary ammonium salt,
- ii. about 4 to about 8 percent of dimethyl alkyl amine oxide, wherein said alkyl is a mixture having the chain-length distribution of coconut oil,
- iii. about 5 to about 35 percent of a low molecular weight alkylbenzenesulfonate selected from the group consisting of sodium toluenesulfonate and sodium xylenesulfonate,
- iv. about 1.5 to about 10 percent of isopropanol,
- v. about 0 to about 0.5 percent of hydroxyethylcellulose, and
- vi. about 39.5 to about 86.5 percent water, said percentages being by weight, whole composition basis.

Having described the invention, the Examples of which as described hereinabove are illustrative and not intended to be limiting, we hereby set forth the manner in which we desire to claim the invention, the scope of which is to be limited only by the appended claims.

What is claimed is:

1. A clear, single phase, liquid fabric softener composition comprising

- i. about 2 to about 20 percent of dialkyl dimethyl quaternary ammonium salt conforming to the formula

35

40

wherein R₁ and R₂ are independently selected from the group consisting of

45

50

and

Radical II: $\text{CH}_3(\text{CH}_2)_y-$ and mixtures thereof, where m = 8 through 14 inclusive,

55

y = 11 through 17 inclusive, and

Radical I comprises between about 5 and about 25 percent by weight of the total of R₁ and R₂, and Radical II comprises between about 40 and about

60

60 percent by weight of carbon chains where y is 11 through 14 inclusive, with the remainder being carbon chains where y is 15 through 17 inclusive,

R₃ and R₄ are independently selected from the group consisting of methyl, ethyl, propyl, and isopropyl radicals,

65

R₅ is methyl or ethyl, and

X is an anion selected from the group consisting of chloride, bromide, iodide, methosulfate, and etho-

sulfate, which imparts water dispersibility to the quaternary,

- ii. about 98 to about 80 percent of a solvent for said quaternary ammonium salt, said solvent comprising a solubilizer selected from the group consisting of

- a. arylsulfonates having the formula A-Bz-SO₃M wherein A is H, methyl, dimethyl, or isopropyl, Bz is a benzene nucleus, and M is Na, K, NH₄, or substituted ammonium,
- b. alkanediols having 2-6 carbon atoms,
- c. alkylene glycols having 2-6 carbon atoms,
- d. methyl, ethyl, and butyl monoethers of diethyleneglycol,
- e. 2-methoxy, 2-ethoxy, and 2-butoxy ethanol,
- f. water-soluble quaternary ammonium compounds having the formula R¹R²R³R⁴NCl wherein R¹ is an alkyl group having about 8 to about 14 carbon atoms, R² and R³ are methyl, and R⁴ is benzyl or ethylbenzyl,
- g. N-alkyl sulfobetaines having the formula

30 wherein R is an alkyl group having 10-14 carbon atoms,

h. N-2-hydroxymethyl taurines, wherein the alkyl group has 8 to 10 carbon atoms,

i. amines oxides having the formula R¹R²R³N → O wherein R¹ and R² are selected from the group consisting of methyl, ethyl, propyl, isopropyl and 2-hydroxyethyl, and R³ is selected from the group consisting of alkyl and 2-hydroxyalkyl having about 8 to 14 carbon atoms,

j. phosphine oxides having the formula R¹R²R³P → O wherein R¹ and R² are methyl, and R³ is an alkyl radical having from 10 to about 16 carbon atoms,

k. sulfoxides having the formula R¹R²S = O wherein R¹ is a methyl, ethyl, or a 2-hydroxyethyl radical, and R² is an alkyl radical having about 6 to about 10 carbon atoms, and

l. nonionic surfactants selected from the group consisting of (a) ethylene oxide condensates of aliphatic alcohols having about 8 to about 18 carbon atoms, and (b) of alkylphenols having straight or branched chain alkyl groups with about 6 to about 12 carbon atoms, the ethylene oxide forming oxyethylene groups to the extent of 5 to 30 molar proportions per mole of condensate, and (c) ethylene oxide condensates with polyoxypropylene, having 30 to 90 percent ethylene oxide by weight per molecule, and mixtures thereof, said solubilizer being present in proportions ranging from about 4 to about 43 percent, whole composition basis, the balance being essentially water, the proportions of said components (a) - (l) being selected to provide a visually clear solution of said quaternary ammonium salt.

2. A clear, single-phase, liquid fabric-softening composition in accordance with claim 1 wherein said qua-

ternary ammonium salt is present in the proportions of about 4 to about 12 percent.

3. A clear, single-phase, liquid fabric-softening composition in accordance with claim 1 wherein said quaternary ammonium salt is present in the proportion of 5 about 6 percent.

4. A clear, single-phase, liquid fabric-softening composition in accordance with claim 1 wherein said solubilizer is selected from the group consisting of arylsulfonates, alkanediols having 2-6 carbon atoms, alkylene 10 glycols having 2-6 carbon atoms, the methyl, ethyl, or butyl monoethers of diethylene glycol, and 2-methoxy, 2-ethoxy, or 2-butoxy ethanol.

5. A clear, single-phase, liquid fabric-softening composition in accordance with claim 1 wherein said quaternary ammonium salt is present in the proportions of about 5-7 percent, said amine oxide is dimethyl coco 15 amine oxide in the proportions of about 4-9 percent and said isopropanol is present in the proportions of about 3-15 percent, the proportions of said dimethyl 20

coco amine oxide and isopropanol being selected to provide a visually clear solution.

6. A visually clear fabric softening composition comprising

- i. about 3 to about 7 percent of a quaternary ammonium salt having a composition in accordance with claim 1,
- ii. about 4 to about 8 percent of dimethyl alkyl amine oxide, wherein said alkyl is a mixture having the chain-length distribution of coconut oil,
- iii. about 5 to about 35 percent of a low molecular weight alkylbenzenesulfonate selected from the group consisting of sodium toluenesulfonate and sodium xylenesulfonate,
- iv. about 1.5 to about 10 percent of isopropanol,
- v. about 0 to about 0.5 of hydroxyethylcellulose, and
- vi. about 39.5 to about 86.5 percent water, said percentages being by weight, whole composition basis.
